UNITED STATES PATENT OFFICE.

JACOB SOLOMON, OF NEW YORK, N. Y., ASSIGNOR TO KIDDIE GARMENT CO. INC., OF NEW YORK, N. Y., A CORPORATION OF NEW YORK.

DESIGN FOR A CHILD'S OUTER GARMENT.

60,065.

Specification for Design.

Patented Dec. 20, 1921.

Application filed January 29, 1921. Serial No. 441,058. Term of patent 3½ years.

To all whom it may concern:

Be it known that I, JACOB SOLOMON, a citizen of the United States, residing at New York, in the county of New York and State of New York, have invented a new, original, and ornamental Design for a Child's Outer Garment, of which the following is a specification, reference being had to the accompanying drawings, forming part thereof.

I claim:

The ornamental design for a child's outer garment, as shown.

JACOB SOLOMON.
